(57) **CLAIM**

The ornamental design for a bottle, as shown and described.

DESCRIPTION

FIG. 1 is a top perspective view of a first embodiment of a bottle showing my new design;

FIG. 2 is bottom perspective view of the bottle shown in FIG. 1;

FIG. 3 is a front view of the bottle shown in FIG. 1, with the rear view being a mirror image thereof;

FIG. 4 is a left side view of the bottle shown in FIG. 1, with the right side view being a mirror image thereof;

FIG. 5 is a top view of the bottle shown in FIG. 1;

FIG. 6 is a bottom view of the bottle shown in FIG. 1;

FIG. 7 is a top perspective view of a second embodiment of the bottle;

FIG. 8 is bottom perspective view of the bottle shown in FIG. 7;

FIG. 9 is a front view of the bottle shown in FIG. 7, with the left side view, right side view, and rear view being mirror images thereof;

FIG. 10 is a top view of the bottle shown in FIG. 7;

FIG. 11 is a bottom view of the bottle shown in FIG. 7;

FIG. 12 is a top perspective view of a third embodiment of the bottle;

FIG. 13 is bottom perspective view of the bottle shown in FIG. 12;

FIG. 14 is a front view of the bottle shown in FIG. 12, with the rear view being a mirror image thereof;

FIG. 15 is a left side view of the bottle shown in FIG. 12, with the right side view being a mirror image thereof;

FIG. 16 is a top view of the bottle shown in FIG. 12;

FIG. 17 is a bottom view of the bottle shown in FIG. 12;

FIG. 18 is a top perspective view of a fourth embodiment of the bottle;

FIG. 19 is bottom perspective view of the bottle shown in FIG. 18;

(Continued)

FIG. 20 is a front view of the bottle shown in FIG. 18, with the left side view, right side view, and rear view being mirror images thereof;

FIG. 21 is a top view of the bottle shown in FIG. 18; and, FIG. 22 is a bottom view of the bottle shown in FIG. 18. The dot-dash broken lines represent the bounds of the claimed design and form no part thereof. The dashed broken lines in the drawings depict portions of the bottle form no part of the claimed design.

1 Claim, 18 Drawing Sheets
